UNITED STATES PATENT OFFICE.

ARTHUR W. CLAPP, OF SAN FRANCISCO, CALIFORNIA, ASSIGNOR TO FRANK E. MIX,
OF MINNEAPOLIS, MINNESOTA.

ENVELOP.

1,125,964.

Specification of Letters Patent. Patented Jan. 26, 1915.

Application filed February 7, 1914. Serial No. 317,196.

To all whom it may concern:

Be it known that I, ARTHUR W. CLAPP, a citizen of the United States, residing at San Francisco, in the city and county of San

Francisco and State of California, have invented certain new and useful Improvements in Envelops, of which the following is a specification.

My invention relates to envelopes and particularly to the type of envelop which is used for transmission in the mails of money or documents of relatively great value.

The object of my invention is to provide an envelop for the above purpose formed with permanently sealed end flaps of relatively small width and having a folding sealing flap of such shape that the seams of the end flaps will be covered by the gum of the folding flap so that said end flaps are additionally secured to the body of the envelop by said folding flap, and forming said folding flap with a cut-away portion at the center thereof which removes the major part of the body of the folding flap and gives a sealing surface of relatively large extent. By these means the envelop thus formed will be very perfectly and efficiently sealed so as to have no exposed seam edges and at the same time will be relatively light when the character of said envelop and the nature of the stock used therein is considered.

The full objects and advantages of my invention will appear in connection with the detailed description thereof and are particularly pointed out in the claim.

In the drawings, illustrating the application of my invention in one form, Figure 1 is a view of my improved envelop with the flap extended. Fig. 2 is a similar view with the flap closed.

The sides of the body 10 of the envelop are secured together at the ends by narrow flaps 11 and 12 securely gummed upon the body 10. Preferably a portion of the sides 45 is folded over with the sealing flap 13 upon a line indicated at 14. The flap 13 has the sides thereof extending at a very slight angle inwardly from the end edges of the envelop, and the interior portion of the flap 13 50 is cut away, as indicated at 15, preferably along a circular line. The gum is applied in a broad strip 16, 17 down each side of the end edges of the flap 13 and in a similar

strip 18 along the inwardly curved edge 15, the strip of gum 18 preferably lapping over 55 upon the upper part of side 10, as indicated at 19.

When the above envelop is turned down into sealing position, as shown in Fig. 2, the gum strips 16 and 17 will lap over the seam 60 of the end flaps 11 and 12, part of said gum adhering to the flaps 11 and 12 and part to the body portion 10 of the envelop. The extended strip 18 will seal uniformly upon the flap surface of side 10, the portion 19 sealing 65 the inturned edge of said side upon the body of the side 10. When so sealed, as clearly indicated, the envelop has a much extended sealing portion on the flap adhering to the side of the envelop, and the seams of the end 70 flaps 11 and 12 will be overlapped by this sealing surface comprised in the gummed portions 16 and 17. At the same time, by reason of the cut out portion 15, the movable flap will be relatively light in weight and 75 comprising a small amount of material while at the same time providing an exceedingly effective and widely extended sealing surface. This not only results in a saving in weight of material and consequent saving of 80 postage but in an adhering surface which may be more effectively applied in sealing the envelop.

I claim:

An envelop having narrow end flaps secured to the body of the envelop, a sealing flap formed of an extended portion of one side of the envelop, a less extended portion of the other side of the envelop being folded over with said sealing flap and comprising 85 a portion thereof, said sealing flap being formed with gummed portions for overlying the edges of the end flaps and being cut away between said end sealing portions to a point near the edge of the side of the envelop which is turned over with the sealing flap, and having a strip of gum extending 90 along the edge of said cut-away portion and upon a portion of said folded over side. 95

In testimony whereof I affix my signature 100 in presence of two witnesses.

ARTHUR W. CLAPP.
